(57) **CLAIM**

The ornamental design for a water distribution apparatus, as shown and described.

DESCRIPTION

FIG. 1 depicts a perspective view of a water distribution apparatus, showing the novel design;

FIG. 2 depicts a front view of a water distribution apparatus, showing the novel design;

FIG. 3 depicts a rear view of a water distribution apparatus, showing the novel design;

FIG. 4 depicts a side view of a water distribution apparatus, showing the novel design;

FIG. 5 depicts an opposing side view of a water distribution apparatus, showing the novel design;

FIG. 6 depicts a top view of a water distribution apparatus, showing the novel design;

FIG. 7 depicts a bottom view of a water distribution apparatus, showing the novel design;

FIG. 8 depicts a perspective view of a second embodiment of a water distribution apparatus showing the novel design;

FIG. 9 is a front view thereof;

FIG. 10 is a rear view thereof;

FIG. 11 is a side view thereof; and,

FIG. 12 is an opposing side view thereof.
